UNITED STATES PATENT OFFICE.

WILLARD C. LIPE, OF SYRACUSE, AND JOHN W. COUGHTRY, DECEASED, LATE OF SYRACUSE, NEW YORK, BY STELLA S. COUGHTRY, ADMINISTRATRIX, OF SYRACUSE, NEW YORK.

MOTION-TRANSMITTING-CONTROLLING MEANS.

1,310,561.

Specification of Letters Patent. Patented July 22, 1919.

Original application filed November 16, 1906, Serial No. 343,762. Divided and this application filed March 23, 1915. Serial No. 16,483.

To all whom it may concern:

Be it known that WILLARD C. LIPE, a citizen of the United States, and a resident of Syracuse, in the county of Onondaga and State of New York, and JOHN W. COUGHTRY, late a citizen of the United States, and a resident of Syracuse, county and State aforesaid, deceased, did invent a new and useful Motion - Transmitting - Controlling Means, of which the following is a specification.

This invention has for its object a particularly simple and efficient means for controlling the transmission of power from driving to driven mechanism, which means is particularly simple in construction and highly efficient in use, and especially adapted to control the transmission of power from the driving means to the rolling mechanism of cigar making machines, such as described in our application Sr. No. 343,762, filed Nov. 16, 1906, of which application this is a division. The invention consists in the novel combinations and constructions hereinafter set forth and claimed.

In describing this invention, reference is had to the accompanying drawings, in which like characters designate corresponding parts in all the views.

Figure 1 is a plan of one form of this controlling mechanism.

Fig. 2 is an elevation, partly in section, looking to the left in Fig. 1, one form of driving element and driven element adapted to be controlled by this controlling means being also shown.

Fig. 3 is a view similar to Fig. 2, showing the operation of the driving and driven elements, the driven element being shown as approaching its starting position in engagement with the controlling means.

Fig. 4 is a sectional view on line A—A, Fig. 1.

This invention comprises, generally, driving and driven elements, means for controlling the transmission of power from the driving to the driven element, and a plurality of starting members, the effective operation of each of which is controlled through the controlling means by the other of said members. The driving and driven

elements may be of any suitable construction.

As here shown, the driving element includes a shaft 1 and a ratchet wheel 2 thereon, and the driven element is here shown as a rotating part 3 loosely mounted on the shaft 1 and a pawl 4 carried thereby and shiftable into and out of engagement with the ratchet wheel 2 and being normally out of engagement therewith. The ratchet wheel 2 and the pawl 4 constitute clutch members by means of which power is transmitted from the driving element to the driven element, the driven clutch member 65 4 being shiftable into and out of connection with the driving clutch member 2.

The means for controlling the transmission of power controls the shifting or the positioning of the shiftable clutch member 70 or pawl 4 and this controlling means includes two sections movable together as a unit, one of these sections being shiftable relatively to the other and being normally in what for convenience is termed a neutral 75 position with respect to a pair of starting members, either one of which starting members is initially movable into engagement with the shiftable section to shift said section relatively to the other section, out of 80 its neutral position and into the path of the other starting member, which when operated shifts the sections together as a unit out of operative position, that is, out of engagement with the pawl 4 to permit the pawl 85 4 to engage the ratchet wheel 2.

A spring 5 acts on the tail of the pawl 4 to move said pawl into operative engagement with the ratchet wheel 2, and said pawl is normally held out of its operative position 90 and against the action of its spring 5 by yielding means as a spring 6 associated with the controlling means. When the controlling means is shifted to carry the spring 6 out of engagement with the tail of the 95 pawl 4, obviously the pawl will be shifted into engagement with the ratchet wheel by the spring 5.

In this embodiment of our invention, the two sections of the controlling means are respectively a slide or carrier 7 movable along a guide 8 in a support 9, and a lever 10 piv-

oted intermediate of its ends at 11 to the carrier or slide 7, said lever 10 extending lengthwise of the slide. The slide 7 is provided with a head 12 at its advance end 5 upon which the spring 6 is mounted.

The support 9 may be any suitable part of the frame of the machine, and is usually a bracket projecting from the main frame of the machine equipped with this controlling 10 means, and the section 7 is held in the guide 8 by suitable means as plates 13 lapping the side margins of the slide or carriage 7 and held in position by screws 14. The lever 10 normally occupies a neutral position and is 15 shiftable to either side of the neutral position, as indicated in dotted lines in Fig. 1.

The sections 7 and 10 are normally held so that the spring 6 engages the tail of the pawl 4, by means of a spring 15 interposed 20 between opposing shoulders 16, 17 on the support 9 and the section or slide 7, and as here shown, the spring is a compression spring arranged in a passage 18 formed in the support 9 below the guide 8 in which the 25 slide 7 moves, the closed end of this passage 18 constituting the shoulder 16. The shoulder 17 associated with the slide 7, is a pin depending from the slide 7 through a slot 19, see Fig. 4, into the passage 18.

30 20 and 21 are the starting members as levers pivoted at 22 upon a common axis, corresponding arms 23, 24 of the levers being arranged to coact with the rear end of the section or lever 10, either to shift the 35 same on its pivot or to engage the lever 10 when it has been shifted by the other starting lever.

As here shown, the arms 23, 24 of the 40 levers are provided, respectively, with oppositely arranged inclined or cam faces 25, 26 and with shoulders 27, 28 for pushing against the lever 10 in order that both sections 7, 10 may be moved as a unit.

The section or lever 10 of the controlling 45 means is normally in its starting or neutral position, as indicated in full lines in Fig. 1. When the lever 20 is operated the cam face 25 of the arm 23 thereof engages at one side of the rear end of the controlling lever 10, 50 that is, the upper side of the lever 10 in Fig. 1, and moves the rear end of said lever downwardly so that a portion of said rear end is in the path of the shoulder 28 of the arm 24 of the other starting lever 21. Hence, 55 when said lever 21 is operated, its arm 24 will push against the rear end of the lever 10 and move the slide 7 and lever 10 rectilinearly as a unit and carry the spring 6 out of engagement with the tail of the pawl 4 so that said pawl 4 is moved by the spring 5 into the path of the teeth of the revolving ratchet wheel 2 and the driven element 3, which carries the pawl 4, is rotated with the wheel 2.

60 65 If the lever 21 is first pressed, its arm 24

is moved into the position indicated in dotted lines in Fig. 1 and shifts the lever 10 as indicated in dotted lines so that its rear end is in the path of the shoulder 27 of the arm 23 of the starting lever 20. Hence upon 70 the operation of the starting lever 20, the slide 7 and lever 10 are actuated as a unit as before.

When the starting force is removed from the levers 20 and 21, they are returned to 75 their starting positions, by a spring 29, and the slide 7 is returned to its starting position by the spring 15. The lever 10 is shifted to its central or neutral position, indicated in full lines in Fig. 1 during the return 80 movement of the slide 7 under the influence of the spring 15, by suitable means here shown as a spring plate 30 fixed at one end by screws 31 to the plates 13, and having at its other or free end a suitable T-shape 85 slot 32 in which is normally located a shoulder 33 provided on the lever 7. This shoulder is formed with a beveled face 34, Fig. 4, for forcing the free end of the spring upwardly after the lever 10 is shifted to its 90 right or left position as indicated in dotted lines, Fig. 1, and the slide 7 is actuated. When the lever 10 is in either of its shifted positions, obviously, the shoulder will not be aligned with the leg of the T-shape slot, but 95 will be in one of the ends of the head of the T-shape slot and hence during the movement of the slide 7, the shoulder 33 must pass under the spring plate.

When, however, the pin has passed clear 100 of the spring plate 30, and the slide 7 and lever 10 are being returned to their starting position under the influence of the spring 15, the shoulder 33 engages one or the other of the converging cam faces 35 forming the 105 entrance of the leg of the T-shape slot, and one of these converging faces obviously will swing the lever 10 on its pivot into its starting position shown in full lines in Fig. 1. The spring plate with its cam faces 35 constitute means for returning the pivoted lever 10 to its central or neutral position.

This controlling lever mechanism is particularly advantageous when two operators are working on the same side of the cigar 110 making machine disclosed in the pending application referred to, as it prevents one operator from starting the machine when the other operator is not ready.

Although this mechanism is particularly 115 advantageous in connection with cigar making machines, obviously it may be used in other situations.

What we claim is:

1. The combination of driving and driven 120 elements each including a clutch member, one clutch member being shiftable into and out of engagement with the other clutch member and being normally out of engagement therewith, means tending to move the 130

shiftable clutch member into position to coact with other clutch member, means for holding the shiftable clutch member disengaged from the other clutch member, the 5 last mentioned means being shiftable into and out of operative position relatively to the shiftable clutch member and including a shiftable part, and a plurality of independently movable starting members, one starting member being arranged to shift said shiftable part into position to coact with the other starting member whereby when the latter is operated said holding means is shifted relatively to the shiftable clutch 10 member, substantially as and for the purpose described.

2. The combination of driving and driven elements, each including a clutch member, the clutch member of one of said elements 20 being shiftable in a plane at an angle to the axis of the said elements and being normally out of engagement therewith, means tending to move the shiftable clutch member into position to coact with the other clutch 25 member, means for holding the shiftable clutch member disengaged from the other clutch member and means for moving the holding means from its operative position, substantially as and for the purpose set 30 forth.

3. The combination of driving means including a ratchet wheel and driven means including a pawl normally disengaged from the ratchet wheel and movable into engagement with said wheel and being revoluble therewith for transmitting motion, and a spring for automatically moving the pawl into position to coact with the ratchet wheel, yielding means for forcing the pawl from 35 its operative position in engagement with the ratchet wheel and for holding the pawl in its inoperative position against the action of the spring, and means for moving the holding means into and out of the path 40 in which the pawl travels with the ratchet wheel, substantially as and for the purpose specified.

4. The combination of driving and driven elements, means for connecting the driving 50 and driven elements, and a plurality of independently movable starting members for controlling the operation of the connecting means, each starting member being arranged to control the operation of said connecting 55 means by the other starting member, substantially as and for the purpose set forth.

5. The combination of driving and driven elements, the driven element including a shiftable clutch member normally out of 60 engagement with the driving element, and shiftable into engagement therewith, a plurality of independently movable starting members for effecting the shifting of the clutch member into engagement with the driving element, and controlling means be-

tween the clutch member and the plurality of starting members, substantially as and for the purpose described.

6. The combination of driving and driven elements, the driven element including a shiftable clutch member normally out of engagement with the driving element, and shiftable into engagement therewith, a plurality of independently movable starting members for effecting the shifting of the 70 clutch member into engagement with the driving element, and controlling means between the clutch member and the plurality of starting members, the controlling means including a part normally occupying a neutral position and shiftable from neutral position by either starting member into the path of the other, substantially as and for the purpose specified.

7. The combination of driving and driven 85 elements, the driven element including a shiftable clutch member normally out of engagement with the driving element and shiftable into engagement therewith, a plurality of independently movable starting 90 members, and means between the clutch member and the starting members for effecting the engagement of the clutch member and the driving element upon the operation of both starting members, substantially as 95 and for the purpose set forth.

8. The combination of driving and driven elements, the driven element including a clutch member normally out of engagement with the driving element and shiftable into 100 engagement therewith, and means tending to move said clutch member into position to coact with the driving element, a sliding member normally holding the clutch member in its inoperative position, means for normally 105 forcing the sliding member in one direction into co-operative relation with said clutch member, and operating means for moving the sliding member in the reverse direction, substantially as and for the purpose described.

9. The combination of driving and driven elements, the driven element including a clutch member normally out of engagement with the driving element and shiftable into 115 engagement therewith, controlling means normally holding the clutch member out of engagement with the driving element, the controlling means including two sections, one being shiftable relatively to the other, 120 and starting means for successively shifting one section relatively to the other and moving the sections together as a unit from their operative position, substantially as for the purpose specified.

10. The combination of driving and driven elements, the driven element including a shiftable clutch member normally out of operative engagement with the driving element, and shiftable into engagement there-

with, and means tending to move the clutch member into position to coact with the driving element, controlling means for holding the clutch member out of engagement with the driving element, including two pivotally connected sections, and starting means for rocking one section relatively to the other and for coacting with the section so rocked to shift both sections as a unit, substantially as and for the purpose set forth.

11. The combination of driving and driven elements, the driven element including a shiftable clutch member normally out of engagement with the driving element and shiftable into engagement therewith, and means tending to move and hold the clutch member in position to coact with the driving element, controlling means for normally holding the clutch member out of engagement with the driving element, including two pivotally connected sections, and means tending to force said sections into operative position, and a plurality of manually operative starting members, one operating to rock one section relatively to the other into the path of the other starting member, and the other starting member operating to shift the sections together as a unit out of operative position, substantially as and for the purpose described.

12. The combination of driving and driven elements, the driven element including a shiftable clutch member normally out of engagement with the driving element and shiftable into engagement therewith, and means tending to move and hold the clutch member in position to coact with the driving elements, controlling means for holding the clutch member out of engagement with the driving element, including two pivotally connected sections, and means tending to force said sections into operative position, and a plurality of manually operated starting members, either member operating to rock one section relatively to the other into the path of the other starting member, and the latter starting member operating to shift the sections together as a unit out of operative position, substantially as and for the purpose specified.

13. The combination of driving and driven elements, the driven element including a shiftable clutch member normally out of engagement with the driving element and shiftable into engagement therewith, and means tending to shift the clutch member into position to coact with the driving element, controlling means coacting with the clutch member and including two sections, the sections being shiftable as a unit, and one being shiftable from its normal position relatively to the other section preliminary to the shifting of the sections as a unit, means for shifting the sections together as a unit in one direction, and for shifting one

section preliminary to the shifting of the sections as a unit, means for shifting said sections as a unit in the reverse direction, and means for returning the shiftable section relatively to the other section to its normal position during the reverse movement of said sections, substantially as and for the purpose set forth.

14. The combination of driving and driven elements including respectively a ratchet wheel and a pawl for coacting with the ratchet wheel, the pawl being normally out of engagement with the ratchet wheel and shiftable into engagement therewith, and movable with the ratchet wheel when engaged therewith, a spring for holding said pawl into position to coact with the ratchet wheel, controlling means including a rectilinearly movable section coacting with the pawl to hold the same out of engagement with the ratchet wheel, and a second section pivotally mounted on the first section and normally arranged in neutral position, the second section being provided with a shoulder, and a plurality of operating members, one operating to rock the pivoted section from its neutral position into the path of the other starting member, and the other starting member operating to engage the section so rocked and move the sections together as a unit, substantially as and for the purpose described.

15. The combination of driving and driven elements, including respectively a ratchet wheel and a pawl for coacting with the ratchet wheel, the pawl being normally out of engagement with the ratchet wheel and shiftable into engagement therewith, and movable with the ratchet wheel when engaged therewith, a spring for holding said pawl in position to coact with the ratchet wheel, controlling means including a rectilinearly movable section coacting with the pawl to hold the same out of engagement with the ratchet wheel, and a second section pivotally mounted on the first section and normally arranged in neutral position, the second section being provided with a shoulder, a plurality of operating members, one operating to rock the pivoted section from its neutral position into the path of the other starting member, and the other starting member operating to engage the section so rocked and move the sections together as a unit, substantially as and for the purpose described.

16. The combination of driving and driven elements, including respectively a ratchet wheel and a pawl for coacting with the ratchet wheel, the pawl being normally out of engagement with the ratchet wheel and shiftable into engagement therewith, and movable with the ratchet wheel when engaged therewith, a spring for holding said pawl in position to coact with the ratchet wheel, controlling means including a rectilinearly movable section coacting with the pawl to hold the same out of engagement with the ratchet wheel, and a second section pivotally mounted on the first section and normally arranged in neutral position, the second section being provided with a shoulder, a plurality of operating members, one operating to rock the pivoted section from its neutral position into the path of the other starting member, and the other starting member operating to engage the section so rocked and move the sections together as a unit, a spring plate fixed at one end and provided at its free end with a cam, and said free end of the plate being arranged to yield to permit the shoulder on the pivoted section to ratchet under the plate, the cam coacting with said shoulder for rocking the pivoted member into its neutral position, and means for moving the sections as a unit to their normal position, substantially as and for the purpose specified.

17. The combination of driving and driven

elements, controlling means for controlling the transmission of power from the driving to the driven element, said controlling means including two pivotally connected sections, 5 and starting means for rocking one section relatively to the other and for thereafter coacting with the section so rocked to move both sections as a unit, substantially as and for the purpose set forth.

10 17. The combination of driving and driven elements, means for controlling the transmission by power from the driving element to the driven element including two pivotally connected sections, means tending to 15 force said sections as a unit in one direction, and a plurality of manually operated starting members, one serving to rock one section of the controlling means relatively to the other and into the path of the other 20 starting member and the other starting member serving to engage the section so rocked and to move the sections as a unit in the opposite direction to that in which 25 said sections are moved by the second-mentioned means, substantially as and for the purpose described.

18. The combination of driving and driven elements, means for controlling the transmission by power from the driving element 30 to the driven element including two pivotally connected sections, means tending to force said sections in one direction, and a plurality of manually operated starting members, one serving to rock one section of 35 the controlling means relatively to the other section, and into the path of the other starting member, and the other starting member serving to engage the section so rocked, and move the sections as a unit in the opposite 40 direction to that in which said sections are moved by the second-mentioned means, and means for shifting the pivoted section to its neutral position during the movement of the sections as a unit to their 45 starting position, substantially as and for the purpose specified.

19. The combination of driving and driven elements, the driven element including a clutch section shiftable into and out of connection with the driving element, and being 50 normally out of its operative position, means for controlling the shifting of the clutch

member comprising a support, formed with a guide, a slide movable along the guide, the slide having means normally coacting 55 with the clutch member to hold the same out of operative position, and a member pivoted to the slide and normally occupying a neutral position, and a pair of starting levers for coacting with the pivoted member, each 60 starting lever having means for shifting the pivoted member into the path of the other starting member, substantially as and for the purpose set forth.

20. The combination of driving and driven 65 elements, the driven element including a clutch section shiftable into and out of connection with the driving element, and being normally out of its operative position, means for controlling the shifting of the clutch 70 member comprising a support, formed with a guide, a slide movable along the guide, the slide having means normally coacting with the clutch member to hold the same out of operative position, and a member pivoted 75 to the slide and normally occupying a neutral position, a pair of starting levers for coacting with the pivoted member, each starting lever having means for shifting the pivoted member into the path of the other 80 starting member, and means on the support for shifting the pivoted member to its neutral position during the movement of the slide toward its starting position, substantially as and for the purpose described. 85

In testimony whereof we have hereunto signed our names, in the presence of two attesting witnesses, respectively in the city of Washington, D. C., and in the city of Syracuse, county of Onondaga, and State 90 of New York, this 23rd day of March, 1915, and this 15th day of March, 1915.
